UNITED STATES PATENT OFFICE.

ANNIE C. HUNTER, OF PLANT CITY, FLORIDA.

CURTAIN AND SHADE BRACKET.

1,354,974.

Specification of Letters Patent.

Patented Oct. 5, 1920.

Application filed March 5, 1919. Serial No. 280,812.

To all whom it may concern:

Be it known that I, ANNIE C. HUNTER, a citizen of the United States of America, residing at Plant City, in the county of Hillsborough and State of Florida, have invented new and useful Improvements in Curtain and Shade Brackets, of which the following is a specification.

The object of the invention is to provide a neat and effective device adapted to hold both a curtain pole and a shade roller bracket. The device is of such shape that it may be conveniently stamped and formed from a single piece of metal and made at one operation on a stamping press. When completed it is adapted for attachment to a window frame without the use of screws and without marring the latter.

The invention is illustrated and described in a specific embodiment, to which, however, it is not to be restricted. The right is reserved to make such changes or alterations as the actual reduction to practice may suggest, in so far as such changes or alterations are compatible in spirit with the annexed claim.

In the accompanying drawings:

Figure 1 is a view in front elevation of the upper portion of a window frame showing the improved device attached thereto.

Fig. 2 is a perspective view of the device *per se*.

Fig. 3 is an edge elevational view of a portion of a window frame showing the device mounted thereon.

Referring to the drawings, the invention is shown as constituting a combined curtain pole and window shade bracket formed from a single piece of metal—preferably thin flat stock. The stock is bent to form a body portion 1, a leg portion 2, designed to rest on the upper edge of the window frame, this leg portion being at an angle to the body portion 1 and a depending hook portion 3, which connects with the leg portion 2 at the end remote from the body portion 1. The leg portion 2 is of greater length than the window frame 4, is thick, but the lower or free end of the body portion is designed to abut or rest against the front face of the frame. The upper end of

the body portion, therefore, stands spaced away from the window frame when the device is attached, but inclines toward the body portion at its lower or free end where the stock of the bracket is curved as shown at 5 to provide a foot resting against the window frame. 55

To provide a curtain pole support, a tongue 6 is struck from the body portion 1 and this tongue at its free extremity is shaped to provide an upstanding stud 7 with which a curtain pole 8 engages, the latter being trailed or poled diagonally to provide a hole for engagement with this 65 stud 7.

The said roller support comprises a disk-like ear 8 formed at the lower extremity of the body portion by turning the stock of which it is made at right angles. The ear 70 8 is thus formed with the body portion adjacent the curved or foot portion 5 of the latter and of each pair of brackets one ear 8 is formed with a rectangular hole for the reception of the flat stud of a shade roller 75 while the corresponding ear of the other bracket is formed with a round hole for the pivotal engagement of the round stud of the shade roller.

From the foregoing description and the accompanying drawings, it is believed that a clear enough understanding of the invention is to be had to render further description unnecessary.

The invention having been described, 85 what is claimed as new and useful is:

A combined curtain pole and shade roller bracket formed from a single piece of metal bent to form a body portion, a leg connecting with the body portion and a hook portion connecting with the leg the body portion being at an acute angle with the leg portion, and being formed at its lower extremity with a foot formed by curving the stock of which the device is made, the body 90 portion having struck therefrom a curtain pole support and further having formed therewith a disk-like ear adjacent the foot, the ear being formed with a hole for the reception of the stud of a shade roller. 95 100

In testimony whereof I affix my signature.
ANNIE C. HUNTER.
